MARKING MACHINE

Alfred R. Merrill, Beverly, Mass., assignor to
 United Shoe Machinery Corporation, Paterson,
 N. J., a corporation of New Jersey

Application March 31, 1931, Serial No. 526,705

54 Claims. (Cl. 33—189)

This invention relates to machines for use in operating upon the bottoms of boots and shoes and is illustrated herein as embodied in a machine adapted to form a positioning mark in a shoe sole.

It has been found desirable in performing certain operations around the bottom margin of a shoe, such, for example, as the sole-rounding or edge-trimming operations on an attached outsole, to provide a templet located in proper position on the shoe sole and to utilize this templet as a guiding means to control or determine the outline on the shoe followed by the rounding or trimming cutter. If such a templet is to be successfully used, it is necessary that the templet be located in exact predetermined position with respect to the last contours of a shoe in order that the edge produced by the cutter may be used as a guide for subsequent operations, such, for example, as the outseaming operation, or that the outline followed by an operating tool may present a proper appearance in the finished shoe.

An object of this invention is to provide a sole-marking machine for automatically forming a positioning mark on the outsole of a shoe in a predetermined position with respect to the last contours of the shoe. In accordance with this object, one feature of the invention resides in a sole-marking machine having means for positioning a shoe laterally by engagement with the side of the toe, means for positioning the shoe longitudinally by engagement with the end of the toe, means for clamping and supporting the shoe as it is being swung into position, and means for making a mark upon the shoe sole in predetermined relation to said positioning devices. In the illustrated embodiment of the invention, the means for positioning the shoe with respect to a marking tool includes a pair of arms geared together at one end and provided with rolls at their other end which engage the sides of the shoe upper adjacent to the sole to position the shoe laterally with respect to the marking tool, and a swinging arm having a block against which the toe end of the shoe rests, arranged to engage the frame of the machine, for positioning the shoe longitudinally.

Another object of this invention is to provide improved movable shoe-supporting means constructed and arranged automatically to carry a shoe from a jacking position into a predetermined position with respect to an operating tool. To this end, another feature of the invention resides in a machine provided with a work support or jack constructed and arranged for move-

ment into and out of operative position, the support having a normal jacking position out of operative position, and provided with power operated means acting upon initial manual movement of the support toward operative position automatically to continue the movement to present a shoe in predetermined relation to an operating tool. In the illustrated embodiment of the invention, the means for moving the shoe toward its operative position includes a continuously reciprocating drag link having means on one end for engaging the support and being normally held out of operative relation to the support by links or arms which cause the reciprocating link to be held out of engagement with the support until after initial manual movement of the support toward operative position.

Another object of this invention is to provide improved means for forming a mark of predetermined depth in a shoe sole. Another feature of this invention, accordingly, resides in a machine provided with a presser constructed and arranged to engage a work piece and provided with means movable relatively to the presser member to make a mark of predetermined depth in the work piece after the presser member has come into engagement with the work piece. Preferably, and as illustrated, the presser member comprises a sliding sleeve which is constructed and arranged to engage the sole of a shoe before the marking means or prick punch is moved a predetermined distance relatively to the sleeve to make a mark of predetermined depth in a shoe sole after the presser member has engaged the shoe sole.

These and other objects and features of the invention will be apparent from the following detailed description read in connection with the accompanying drawings and the novel features of the invention will then be defined in the appended claims.

40 In the drawings,

45 Fig. 1 is a perspective view of a machine embodying the present invention;

Fig. 2 is a view in side elevation of the machine with parts broken away to show the operating mechanism;

Fig. 3 is a detail view of the work support with its associated operating mechanism;

Fig. 4 is a detail view of the operating mechanism;

Fig. 5 is a view in side elevation of the head of the machine with parts of the machine frame broken away; and

Fig. 6 is a view taken along the line VI—VI of Fig. 5.

The machine illustrating an embodiment of the invention includes a pair of frames 10 which are mounted on a base 12. As illustrated in Fig. 1, the machine is provided with two operating heads, 5 each being supported by the frames 10. The operating heads are identical in construction and only one of these heads will be described in detail. The front portion of the base 12 is provided with a cover 14 to permit access to the mechanism contained therein.

10 Mounted on a horizontally extending portion of the base 12 is an electric motor 16 which has its shaft coupled to a shaft carrying a worm 18 which in turn drives a cam shaft 20 through a worm 15 gear 22. Cams 24 and 26 are secured to the shaft 20 by any suitable means. The cam 24 has a cam track 28 formed therein in which rides a cam roller 30 secured to the lower end of a bell crank lever 32. The lever 32 is pivoted to the machine frame at 34 and controls the movement of a jack or work support, indicated generally by the reference character 36.

15 The work support 36 comprises a last pin carrying spindle 38 pivoted to the frame 10 at 40 and a swinging arm or toe rest 42 which is also pivoted to the machine frame at 40. The spindle 38 is forked at its upper end to receive a pivoted member 44 carrying a last pin 46. The pivoted member 44 is so mounted that the last pin 46 cannot tilt laterally and thus holds a shoe mounted thereon against movement about its longitudinal axis. Rotation of the pivoted member 44 is limited by a stop pin 48 which enters a depression or recess in the pivoted member 44. The last 20 pin 46 and the spindle 38 are normally urged toward the toe rest 42 by a spring 50 which is secured at one end to the pivoted member 44 and at its other to the toe rest 42. The movement of the spindle 38 toward the toe rest 42 is limited by an adjusting screw 52 bearing against a stop 54 on the toe rest 42. The toe rest or support 42 (as shown best in Fig. 1) is provided with a longitudinal slot to receive mechanism for imparting movement to the work support 36. The upper end of the toe rest carries a substantially U-shaped plate 56 having an upper member 58 and a lower block 60. When a lasted shoe is placed on the last pin 46, the spring 50 forces the toe end of the shoe against the lower block 60 and the projecting portion of the outsole lies between the upper member 58 and the block 60 with the surface of the outsole adjacent to the block 60 resting thereon.

25 The mechanism for moving the work support 36 toward and under the operating head comprises cam and lever connections between the cam 24 and the toe rest 42. The bell crank lever 32 is forked at its upper end to receive an arm 62 which is pivoted to the lever 32 by means of a pin 64. Slidably mounted in a boss 66 on the lever 32 is a pin 68 which is normally urged outwardly under the influence of a strong spring 70 against a projection 72 on the arm 62. Coacting surfaces 74 on the lever 32 and the arm 62 limit the clockwise movement of the arm 62 under the influence of the spring 70. The construction just above referred to insures that a stop 76 on the swinging arm 42 will always be brought against a stop 78 on the machine frame thereby insuring that the shoe carried on the support 36 will be brought into proper position beneath the operating head 80 of the machine despite any inaccuracies in, or lost motion between, the parts of the operating mechanism. A drag link 82 is pivoted to the upper end of the arm 62. The

drag link 82 is cut away to form a recess 84 which, under conditions later to be described, is pulled down over a pin 86 extending through the swinging arm 42 under the influence of a spring 88.

5 The lever 32 is continuously reciprocated by the rotating cam 24 and it is necessary, therefore, to provide means under the control of the operator to prevent movement of the support 36 while a shoe is being placed on the support. The drag link 82 is provided with a slot 87, through which passes a pin 88 fastened in a slotted arm 90 which is pivotally secured to the machine frame at 92. The forward end of the arm 90 is provided with cam surfaces 94 which when they are in contact with the pin 86 raise the arm 90 and the pin 88, engaging the upper wall of the slot 87, raise the drag link 82 and prevent the recess 84 from engaging the pin 86. The upper surface of the arm 90 is notched at 96 to receive the lower end 20 of a latch pin 98. The latch pin 98 is secured at its upper end to a latch 100 which, when raised, withdraws the latch pin 98 from the notch 96 and allows the arm 42 to be moved in the direction of the arrow in Fig. 3 until the pin 86, which extends through the arm 42 and beyond the two sides thereof, is brought under the recess 84 in the continuously reciprocating link 82. The latch 100 is normally urged downwardly by a spring 101 to cause the latch pin 98 to engage 30 the notch 96.

25 When the support 36 is being returned from the position shown in Fig. 2 to the position shown in Fig. 3, the forward end of the arm 90 engages a pawl-like member 102 which is pivoted to the swinging arm 42 and is held toward the arm 42 by a spring 104. The member 102 carries a pin 106 which engages a stop 108 which limits the extent of movement of the member 102 under the influence of the spring 104. The surface 110 on 35 the member 102 engages the cam surfaces 94 on the arm 90 and raises the arm 90 so that a notch 112 on the arm 90 engages the pin 86 thereby holding the link 82 out of contact with the pin 86. The arm 42 is limited in its movement to the position shown in Fig. 3 by a rod 114 which is pivoted at one end to the arm 42. The other end of the rod passes through an opening in the machine frame 10 and a spring 116, which encircles the rod between the machine frame and a pair of lock 50 nuts 118, acts as a resilient stop to limit the outward movement of the arm 42. When the latch 100 is raised the arm 42 is moved in the direction of the arrow in Fig. 3 until the pin 86 45 engages a projection 120 on an arm 122 which is 55 pivoted to the frame at 92. In this position the pin 86 is located at a point where it may be caught in the recess 84 of the drag link 82. The arm 122 is forced downwardly by a pin 124 on the link 82 to move the projection 120 out of the path of 60 movement of the pin 86. The support or jack 36 is then moved as a unit to the right by movement of the lever 32 and the link 82 which are operated by the cam 24 until the projection 76 on the arm 42 strikes the stop 78. The spring 70 is 65 compressed by further movement of the lever 32 which allows the lever 32 to complete its movement to the right without danger of breakage to the parts of the machine.

70 As the support 36 carrying a shoe 126 is moving toward the right to the position shown in Figs. 2 and 5, the sides of the upper adjacent to the toe end are engaged by rollers 128 mounted on the ends of arms 130 which are pivoted to the machine frame at 132 and 134. Each arm is 75

provided at its other end with a segment 136 of a gear, the teeth of each segment being in engagement with the teeth of the other segment. The arms 130 are normally urged toward each other by a spring 138. Since the arms 130 are geared together movement of one arm causes a movement of the other so that the shoe 126, regardless of its size, will be properly positioned beneath a prick punch or marking tool 140. When the marking tool 140 is moved downwardly by mechanism, which will presently be described, a spring 142 is stretched and causes the rollers 128 to press against the sides of the upper of the shoe, thus insuring that the shoe will contact with both rollers to position the shoe laterally with respect to an operating tool 140. The rolls 128 are each mounted on pins 144 in such a manner that the rolls are free to move vertically under the action of the operating instrumentalities contained in the machine head. A spring 146 encircles a reduced portion of each roll and causes the roll normally to be held in its upper position. The rolls 128 are spring mounted so that, although they are brought into engagement with the widest part of the toe of the shoe and close up against the welt, they still will have no tendency to tilt the shoe in case the sole and the welt are not beaten out perfectly flat upon one side of the shoe.

The mechanism for operating the marking tool is connected to the cam 26 by means of a system of links and levers. A bell crank lever 148 is pivoted to the machine frame at 34 and at its lower end is provided with a cam roll 159 which engages a cam track 152 in the cam 26. The other end of the bell crank lever 148 is connected by a link 154 to a lever 156 which is fulcrumed to the machine frame at 158. The lever 156 carries a cam roll 160 which contacts, at appropriate times, with a cam surface 162 on one arm of a bell crank lever 164. The other arm of the bell crank lever 164 is connected to one end of the spring 142, referred to above. The lever 156 has pivoted to its other end a bell crank lever 166 one arm of which is provided with a roll 168 which enters a recess in a sleeve or presser member 170. The sleeve 170 is mounted for sliding movement in a guideway 172 formed in the machine head 88. The sleeve 170 is normally urged upwardly by a spring 174 which has one end secured to a cap screw 176 in the lower end of the sleeve. The other end of the bell crank lever 166 has its end portion formed with a surface on the arm 177 (Fig. 5) which engages a roll 178 which is connected to a toggle 180. One link of the toggle 180 is secured to the upper end of the sleeve 170 and the other link of the toggle is fastened to the marking tool or prick punch 140. A spring 184 secured at one end to the toggle joint and at its other end to the machine frame normally tends to break the toggle.

When the link 154 is moved upwardly the lever 156 is rotated in a counterclockwise direction which causes the sleeve 170, through the bell crank lever 166, to be moved downwardly. The spring 184 is of such strength that the toggle 180 is not straightened until the sleeve 170 engages the shoe sole. The bell crank lever 166 then rotates about its axis and straightens the toggle against the tension of the spring 184. At the same time the cam roll 160, which has been moved upwardly, engages the cam surface 162 on the lever 164 and stretches the spring 142 which causes the arms 130 of the bell crank lever to be moved toward the shoe thereby positioning the

shoe properly with respect to the marking tool. While the parts of the machine have been described in detail, it may be well to summarize briefly the operation of the machine. The operator places a lasted shoe 126 on the last pin 46 with the toe end of the shoe against the block 60. The spring 50 will press the toe end of the shoe against the block and maintain it in its proper position. When the shoe has been placed on the support or jack 36, the operator pulls upwardly upon the latch 100. The latch pin 98 is lifted out of the notch 96 which permits the operator to move the support 36 until the pin 86 engages the forward end of the projection 120. Movement of the support also moves the pin 86 away from the notch 112 which causes the arm 90 to drop downwardly. Movement of the link 82 toward the position shown in Fig. 3 causes the arm 122 to be pulled downwardly which moves the projection 120 out of the path of movement of the pin 86. The link 82 then drops downwardly so that the recess 84 engages the pin 86 and the support is moved into operating position. As the support moves into operating position, the hooked end of the arm 90 engages the pawl-like member 102 and rotates it about its axis. After the hooked end has passed out of engagement with the member 102, the member 102 is returned to the position shown in Fig. 3. As the support moves into operating position, the rolls 128 engage the sides of the shoe upper adjacent to the toe end of the shoe to position the shoe laterally with respect to the tool 140. The light spring 138 operates to resist the operation of the rolls 128 and the rolls, accordingly, are not forced against the upper with any great pressure.

During the portion of the cycle of operation that the support is being moved into operating position, the marking mechanism has been held in its upper position as shown in Fig. 2. When the support 36 has carried the shoe into the position shown in Figs. 2 and 5, the support remains at rest until the tool 140 has made a conical depression in the shoe sole. The sleeve 170 which operates as a presser member is carried downwardly by the movement of levers 156 and 166 until the lower end of the sleeve engages the outsole to press the outsole against the rolls 128. When the lever 156 is rotated, the cam roll 160, carried thereon, engages the cam surface 162 on the lever 164 and stretches the spring 142 to increase pressure of the rolls 128 against the upper to position positively the shoe and to hold the shoe in position until after the tool 140 has operated to mark the upper of the shoe sole. The spring 184 which is connected to the toggle 180 is strong enough to prevent the lower arm of the lever 166 from straightening the toggle until the sleeve 170 engages the shoe sole. After the toggle 180 has been straightened and the tool 140 has made a mark in the shoe sole, the sleeve 170 and the tool 140 are then returned to inoperative position and the mechanism for moving the support operates to return the support to its original position. Near the end of the return movement of the support 36 the hooked end of the arm 90 rides over a cam surface 116 on the member 102 thus raising the arm 90 which moves the recess 84 in the drag link 82 out of engagement with the pin 86. The support or jack 36 continues its movement under momentum imparted to it by the drag link until the latch pin 98 engages the notch 96 in the arm 90. The pin 86 on the toe support engages the notch 112 on the arm 90 and, together with the latch pin 98, prevents movement of

the support until the latch pin is raised. The shoe is then removed and another shoe placed on the support in readiness for another cycle of operation of the machine.

5 Having thus described my invention, what I claim as new and desire to secure by Letters Patent of the United States is:

- 10 1. In a sole-marking machine, means for positioning the toe end of a shoe laterally by engagement with the sides of the toe, means for positioning the shoe longitudinally by engagement with the end of the toe, pivoted means for clamping and supporting the shoe as it is being swung into engagement with said positioning means and means for making a mark upon the sole in predetermined relation to said positioning means.
- 20 2. In a sole-marking machine, means for making a position mark upon the sole near the toe end of the shoe, said marking means occupying a relatively fixed position in the machine, means for locating a shoe by engagement with the sides and the end of the toe of the shoe adjacent to the sole in a predetermined position with respect to said marking means, and a movable shoe supporting jack for supporting a shoe as it is moved into the marking position determined by said positioning means.

30 3. In a sole-marking machine, a marking device located in a relatively fixed position and adapted to apply a position mark to the sole of a shoe, means in a predetermined relation to the marking device for determining the position of said shoe with respect to said marking device constructed and arranged to locate the shoe by engagement with both of the sides and the toe end of the shoe, pivoted means for clamping and supporting a shoe as it is being moved into engagement with said positioning means, and means for operating said marking device.

40 4. In a sole-marking machine, means for applying a mark to the sole of a lasted shoe, said means occupying a relatively fixed position in the machine, shoe locating devices in predetermined relation to said marking means constructed and arranged to locate the shoe laterally and longitudinally, machine operated means for effecting final movement of the lasted shoe into a position determined by said locating devices, and means for operating said marking means.

50 5. In a sole-marking machine, means for making a prick mark on the sole, means occupying a relatively fixed position in relation to the marking means for locating a shoe laterally and longitudinally, a swinging shoe supporting arm, means for swinging said arm to bring the shoe into a predetermined position controlled by said positioning means, and means for operating said marking means.

60 6. In a sole-marking machine, means for determining the position of a shoe longitudinally by engagement with the toe end of the shoe, a swingingly mounted shoe supporting arm adapted to receive and carry into operative position an inverted shoe, and means for moving said arm constructed and arranged to bring the shoe into predetermined position with the toe of the shoe in firm engagement with the toe engaging means, and means for applying a position mark to the bottom of the sole of the shoe thus supported.

70 7. In a machine for operating on shoes, an operating tool for operating on a shoe sole, a sleeve in which said operating tool slides, means for reciprocating the sleeve, toggle mechanism connected to the sleeve and to the tool for moving the tool relatively to the sleeve to make a

mark of predetermined depth in the shoe sole, and means for automatically moving the shoe into position beneath the operating tool and for returning the shoe to its original position.

75 8. In a machine for marking shoe soles, a marking tool, a work support, means for moving the work support to position a shoe in predetermined relation to the marking tool and for returning the support to its original position, a sleeve mounted in the machine and adapted to engage the sole of the shoe, and means for moving the marking tool after the sleeve has engaged the shoe sole to make a mark of predetermined depth in the shoe sole.

15 9. In a sole-marking machine, a marking tool for making a depression of predetermined depth in a shoe sole, means arranged to engage the toe end of a shoe to position the shoe laterally with respect to said marking tool, means for supporting the shoe for movement into position 20 beneath the marking tool to position the shoe longitudinally with respect to said tool, and power operated means for automatically moving the supporting means into position and for returning the supporting means to original position.

25 10. In a sole-marking machine, a machine head, a marking tool, a sleeve mounted in the machine head and in which the marking tool is reciprocated, means for positioning a shoe laterally relatively to said tool, means for determining the longitudinal position of the shoe with respect to said marking tool, means for supporting the shoe for movement into engagement with said positioning means, and actuating means for said supporting means, said means including a 35 reciprocating link having a hooked end for engaging said supporting means, said link being normally inoperative and adapted to engage the supporting means upon initial manual movement of the supporting means.

40 11. In a sole-marking machine, a marking tool, means for positioning a shoe laterally with respect to said marking tool, means for supporting a shoe and arranged to position a shoe longitudinally with respect to said marking tool, means 45 engaging said supporting means for normally maintaining the supporting means in inoperative position, manually operated means for releasing the supporting means to permit the supporting means to move toward operative position, and means adapted to engage said supporting means to move said means into a predetermined position beneath the marking tool and to return the supporting means to inoperative position.

45 12. In a sole-marking machine, a tool for making a mark on a sole, a movable support for an inverted lasted shoe comprising relatively movable arms one of which is provided with a last spindle and the other of which is arranged to support the toe end of the shoe, means for positioning said shoe with respect to the marking tool when moved into engagement therewith by said arms, and means interconnecting said arms for movement together as a unit.

50 13. In a sole-marking machine, a tool for making an imprint upon the sole of the shoe, a support for an inverted lasted shoe comprising a pair of arms mounted on a common pivot and adjustable relatively to each other to accommodate shoes of different sizes, one of said arms being provided with a last spindle and the other of said arms having a support for the toe end of the shoe, said latter arm being also provided with a gaging surface for contact with the toe end of the lasted upper, and means for interconnect-

40

45

50

55

60

65

70

75

ing said arms for movement together as a unit whereby movement of said arms until the latter arm reaches a predetermined position results in positioning the shoe in a predetermined relation to the marking tool.

14. In a sole-marking machine, a sole marking tool, means for supporting a lasted shoe in inverted position to receive the imprint of said tool comprising a pair of arms mounted on a common pivot below the tool, one of said arms being provided with a last spindle mounted for swinging movement in the plane of the two arms, the other of said arms being provided with toe supporting means and having a positioning surface for engaging the toe end of the lasted upper, and a spring connection between said arms constructed and arranged to tilt said spindle to hold the toe end of the shoe against its support and the positioning surface.

15. In a sole-marking machine, a tool for marking the bottom of a sole, means for supporting a lasted shoe in inverted position to receive the imprint of said tool comprising a pair of arms mounted on a common pivot below the tool, a spring tending to draw said arms together, one of said arms being arranged to support the heel end of the shoe and the other of the arms being arranged to support the toe end of the shoe, and means on said latter arm for overhanging the toe end of the sole to prevent accidental upward displacement of the shoe as the latter is moved into marking position.

16. In a sole-marking machine, means for making a positioning mark upon the sole near the toe end of the shoe, said marking means occupying a relatively fixed position in the machine, means for locating a shoe by engagement with the sides and the end of the toe of the shoe adjacent to the sole in predetermined position with respect to said marking means, a movable shoe-supporting jack to support the shoe as it is moved into marking position, said supporting jack being normally in inoperative position with respect to the marking means and constructed and arranged to be moved initially by the operator, and power operated means for automatically effecting final movement of the shoe into marking position and returning the shoe to its original position.

17. In a sole-marking machine, means for applying a mark to the sole of a shoe, means for positioning the shoe laterally with respect to said marking device cam-operated means for supporting the shoe and moving the shoe into a predetermined longitudinal position relatively to said positioning means, and toggle-operated means for operating the marking means.

18. In a sole-marking machine, means for operating upon a shoe sole, and means for positioning the shoe laterally with respect to said operating means, said positioning means including a pair of arms geared together at one end, rolls at the other ends of said arms adapted to engage the upper of the shoe adjacent to the shoe sole, said arms normally being urged toward each other by a light spring, and means for urging said arms together prior to the operation of the operating means to increase pressure on the shoe upper to insure lateral positioning of the shoe.

19. A work support having, in combination, means for supporting the heel end of a shoe, means engaging the toe end of the shoe for positioning the shoe in predetermined relation to an operating tool, means for maintaining and locking the support in inoperative position, means

for unlocking the support operable only after an initial movement has been imparted to the supporting means, and means for automatically moving the shoe the final distance into a predetermined position with respect to said operating means and to return the support to inoperative position.

20. In a sole-marking machine, a marking tool adapted to mark the bottom of a sole, movable means for supporting a lasted shoe in inverted position to receive the imprint of said tool and constructed and arranged to support the heel end of the shoe against tilting movement and to allow adjustment of the toe end of the shoe, and shoe engaging means constructed and arranged to engage the sides of the upper and to underlie the overhanging lateral edges of the sole to support them.

21. In a sole-marking machine, a marking tool adapted to mark the bottom of a sole, means for supporting a lasted shoe in inverted position to receive the imprint of said tool comprising a movable support constructed and arranged to support the heel end of the shoe against tilting movement and to allow adjustment of the toe end of the shoe, and shoe engaging means constructed and arranged to engage the sides of the upper and to underlie the overhanging lateral edges of the sole, said sole underlying means being vertically depressible.

22. In a sole-marking machine, a frame, a marking tool for the sole of a shoe, movable means for supporting a lasted shoe to receive the imprint of said tool, means for determining the position of the shoe on said supporting means constructed and arranged to engage the toe end of a lasted upper, and coacting means on said frame and said movable supporting means for determining the longitudinal position of the shoe relatively to said marking tool as the supporting means is moved into operative position.

23. In a sole-marking machine, a frame, a marking tool, means for supporting a lasted shoe in inverted position to receive the imprint of said tool comprising a last spindle and a toe support, said toe support being constructed and arranged to engage the toe end of a lasted upper, interengaging surfaces on said frame and said toe support for determining the longitudinal position of the shoe with respect to the marking tool, and yielding means for moving said supporting means to bring the shoe into operative position with said surfaces in firm engagement.

24. In a sole-marking machine, a marking tool, a support constructed and arranged to position a shoe longitudinally with respect to the marking means, means adapted to engage the upper of the shoe adjacent to the toe end to position the shoe laterally as it is being positioned longitudinally, presser means adapted to engage the sole of the shoe, and means for moving the marking tool when the presser means engages the shoe sole to form a mark of predetermined depth in the shoe sole.

25. In a sole-marking machine, means for marking a shoe sole, positioning devices for locating a shoe laterally with respect to the marking tool, means for supporting the shoe and for moving the shoe into position beneath the marking means, and means for operating said supporting means, said supporting means including a yieldable connection to said operating means, and a fixed abutment for insuring that the shoe will be brought into proper position with respect to the marking tool.

26. In a sole-marking machine, means for positioning the toe end of a shoe laterally by engagement with the sides of the upper adjacent to the sole of the shoe, means for positioning the shoe longitudinally by engagement with the end of the toe, means for supporting a shoe as it is positioned, and toggle-operated means for making a mark of predetermined depth in a shoe sole regardless of the thickness of said sole in predetermined relation to said positioning means.
27. In a sole-marking machine, an operating tool, means for supporting a shoe and positioning the shoe longitudinally, said supporting means being operated automatically upon initial manual movement toward operating position to locate the shoe longitudinally with respect to the operating tool, and means for positioning the toe end of a shoe laterally by engagement with the sides of the toe, said lateral positioning means being constructed and arranged to apply light pressure to the sides of the shoe adjacent to its toe end during movement of the shoe while it is being positioned longitudinally and applying greater pressure to the sides of the shoe prior to the operation of said operating tool.
28. In a sole-marking machine, a marking tool, means for positioning a shoe in predetermined relation to the marking tool, presser means constructed and arranged to press against the sole of a shoe located by said positioning means, a toggle connected to the presser means and to the marking tool, and means for moving the presser against the work and for straightening the toggle to cause the marking tool to apply a mark to the shoe sole.
29. In a sole-marking machine, means for making a mark of predetermined depth upon the sole, means for determining the position of a shoe laterally and longitudinally with respect to said marking means, a reciprocating sleeve adapted to press against the shoe sole, and means operating through a toggle to move the marking tool with respect to said sleeve after the sleeve has pressed against the sole.
30. In a sole-marking machine, means for making a positioning mark upon a shoe sole, means for supporting the shoe and positioning the shoe longitudinally with respect to the marking means, said last-mentioned means being constructed and arranged automatically to carry the shoe into operative relation to said marking means and to return the shoe to its original position after operation of the marking means, a presser member adapted to be moved into engagement with the shoe sole, and means for moving the marking means relatively to the presser member to form a mark of predetermined depth in a shoe sole after the presser member has engaged the shoe sole.
31. In a sole-marking machine, a marking tool, means for positioning a shoe laterally and longitudinally with respect to the marking tool, a sleeve constructed and arranged to engage the sole of the shoe, and means for moving the sleeve into engagement with the shoe and for moving the marking tool a predetermined distance relatively to the sleeve to form a mark on the shoe sole after the sleeve has been brought into engagement with the sole.
32. In a sole-marking machine, a prick punch, means for positioning a shoe laterally with respect to the prick punch, a sleeve constructed and arranged to engage the sole of the shoe, and means for moving the sleeve into engagement with the shoe sole and for moving the prick punch a predetermined distance relatively to the sleeve to form a mark on the shoe sole after the sleeve has been brought into engagement with the shoe sole.
33. In a shoe marking machine, a marking device, a work support constructed and arranged for movement into and out of operative position relatively to said device, said support having a normal work receiving position out of operative relation, continuously reciprocating means adapted to engage said support upon initial movement of the support toward operative position automatically to continue said movement to bring the shoe to said marking device, and means to position said shoe relatively to said marking device.
34. In a sole-marking machine, means for making a mark in a shoe sole, a shoe support constructed and arranged for movement into and out of operative relation to said marking means, said support having a normal work receiving position out of said operative relation, and continuously reciprocating means including a hooked member adapted to engage said support upon initial movement of the support toward operative position automatically to continue said movement to bring the shoe to the marking means in predetermined relation thereto.
35. In a sole-marking machine, means for making a mark in a shoe sole, a shoe support constructed and arranged for movement into and out of operative relation to said marking means, said support having a normal work receiving position out of said operative relation, and means including a hooked link adapted to engage said support upon initial movement of the support toward operative position automatically to continue said movement to present the shoe to the marking means in predetermined relation thereto and to return the support to normal position after operation of the marking means.
36. In a machine for marking shoe bottoms, means for forming a mark on a shoe bottom, shoe supporting means, means for positioning the shoe laterally and longitudinally with respect to said marking means, and means for automatically moving the shoe into operative position with respect to the marking means, said automatic means including a continuously reciprocating link, having a hooked end for engaging the supporting means, means for normally maintaining the link out of operative relation with respect to the supporting means, and means for releasing the last-mentioned means to permit the hooked end of the link to engage the supporting means to move the shoe into operative position with respect to said marking means.
37. In a sole-marking machine, means for forming a mark in a shoe sole, means for positioning the shoe laterally with respect to said marking means, and means constructed and arranged to support a shoe and to position the shoe longitudinally with respect to said marking means, said supporting means including a support for the heel end of the shoe, means engaging the toe end of the shoe, a reciprocating member, and means on the toe support adapted to be engaged by the reciprocating member for automatically moving the shoe into operative position and returning the shoe to its original position.
38. In a machine for marking shoe soles, a marking tool, means for positioning a shoe laterally with respect to said marking tool, a swing-ing shoe supporting arm for supporting the shoe and for positioning the shoe longitudinally with

respect to the marking tool, means for swinging the arm to bring the shoe into a predetermined position controlled by said positioning means, and means operating through a toggle for moving the marking tool to make a prick mark of predetermined depth in a shoe sole.

39. In a sole-marking machine, a toe rest, means for determining the position of a shoe longitudinally by engagement with the toe end of the shoe, supporting means adapted to receive and carry into operative position an inverted shoe, and means for moving said arm constructed and arranged to bring the shoe into predetermined relation with the toe of the shoe in firm engagement with the toe rest, said last-mentioned means being normally held out of engagement with the supporting means and being adapted upon initial movement of the support by the operator to engage the supporting means to move the support to operative position.

40. In a sole-marking machine, a marking tool, means for positioning a shoe laterally with respect to the marking tool, means for supporting a shoe and for positioning the shoe longitudinally with respect to said marking tool, said supporting means being normally out of operative position with respect to said marking tool, and power-operated means for moving the support into operative position for holding the support in said position during the marking operation and for moving the support out of operative position after the marking operation has been effected.

41. In a sole-marking machine, a marking tool, means for positioning a shoe laterally with respect to the marking tool, means for supporting a shoe and for positioning the shoe longitudinally with respect to said marking tool, said supporting means being normally out of operative position with respect to said marking tool, power-operated means for moving the support into operative position, for holding the support in said position during the marking operation, and for moving the support out of operative position after the marking operation has been effected, and means for operating the marking tool to form a mark of predetermined depth on the shoe sole.

42. In a sole-marking machine, a marking tool, means for positioning a shoe laterally with respect to the marking tool, means for supporting a shoe and for determining the longitudinal position of the shoe with respect to said marking tool, said supporting means being normally out of operative position with respect to said marking tool, power-operated means for moving the supporting means into operative position for holding said last-mentioned means in said position during the marking operation and for moving said means out of operative position after the marking operation has been effected, a sleeve constructed and arranged to engage the sole of the shoe, and means for moving the sleeve into engagement with the shoe sole and for moving the marking tool with respect to the sleeve to form a mark of predetermined depth in the shoe sole.

43. In a sole-marking machine, a marking tool, means for positioning a shoe laterally with respect to the marking tool, means for supporting a shoe and for determining the longitudinal position of the shoe with respect to said marking tool, said supporting means being normally out of operative position with respect to said marking tool, power-operated means for moving the support into operative position for holding the support in said position during the marking operation and for moving the support out of operative position after

the marking operation has been effected, a sleeve for engaging the shoe sole, a bell-crank lever having one arm for moving the sleeve into engagement with the shoe sole and another arm for moving the marking tool to form a mark of predetermined depth in the shoe sole.

44. In a marking machine, a marking tool, a presser member for engaging a work piece, and means for moving the presser member into engagement with the work piece, said means being arranged also to move the tool relatively to the presser member to form in a work piece a mark of predetermined depth less than its thickness.

45. In a marking machine, a tool for forming a mark in a work piece, a presser member constructed and arranged to engage a work piece, and means for moving the presser member into engagement with the work piece, said means being arranged also to move the tool relatively to the member to form a mark of predetermined depth in the work piece less than the thickness thereof after the member has been brought into engagement with the work piece.

46. In a marking machine, a sleeve constructed and arranged to engage the sole of a shoe, means for forming a mark of predetermined depth in the shoe sole irrespective of the thickness of the sole, and means for moving the sleeve into engagement with the shoe sole and for moving the marking means relatively to the sleeve to form a mark on the shoe sole after the sleeve has been brought into engagement with the shoe sole.

47. In a marking machine, a marking tool, a sleeve constructed and arranged to be brought into engagement with a shoe bottom, and means for moving said sleeve into engagement with the shoe bottom, said means being arranged also to move the tool a predetermined distance beyond the end of said sleeve to form a mark of predetermined depth in said shoe bottom.

48. In a marking machine, a sleeve constructed and arranged to be brought into engagement with a shoe sole, a marking tool for forming a mark in the shoe sole, a toggle connected to the sleeve and to the tool for moving the tool relatively to the sleeve to form a mark of predetermined depth in a shoe sole, and means for moving the sleeve into engagement with the shoe sole.

49. In a sole-marking machine, a pair of arms geared together at one end, rolls at the other end of said arms for laterally positioning the toe end of a shoe by engagement with the sides of the shoe and constructed and arranged to yield vertically to prevent tilting of the shoe, said arms being normally urged toward each other by a light spring, means for positioning the shoe longitudinally by engagement with the end of the toe, means for supporting the shoe as it is positioned, and means for making a mark upon the sole in predetermined relation to said positioning means.

50. In a sole-marking machine, means for positioning the toe end of a shoe laterally by engagement with the sides of the toe, a movable toe support, a gaging surface on the toe support for contact with the toe end of a shoe for positioning the shoe longitudinally, a fixed abutment, means for supporting the shoe as it is positioned, means for making a mark upon the sole in predetermined relation to said positioning means, and means for moving the toe support against the abutment to determine the longitudinal position of the shoe relatively to the marking means.

51. In a sole-marking machine, means for positioning the toe end of a shoe laterally by engagement with the sides of the shoe, a support

for a lasted shoe comprising a pair of arms mounted on a common pivot and adjustable relatively to each other to accommodate shoes of different sizes, one of said arms being provided with a last 5 spindle and the other of said arms having a support for the toe end of the shoe, said latter arm being also provided with a gaging surface for contact with the toe end of the shoe to position the shoe longitudinally, and means for making a mark 10 upon the sole in predetermined relation to said positioning means.

52. In a sole-marking machine, a tool for forming a mark in a shoe sole, means for positioning the shoe with respect to the marking tool, said means including a pair of arms geared together at one end and provided with rolls at the other end to engage the sides of the shoe upper adjacent to the sole to position the shoe laterally with respect to the marking means, and a swinging arm 15 having an abutment against which the toe end of the shoe rests for positioning the shoe longitudinally.

53. In a machine for marking shoe soles, means

for marking a shoe sole, means for positioning a shoe laterally with respect to said marking means, means for supporting and positioning the shoe longitudinally, and means for moving the shoe toward operative position, said means including a continuously reciprocating drag link having means on one end for engaging the support and being normally held out of operative relation to the supporting means until after initial manual movement of the supporting means toward operative position. 5

54. In a sole-marking machine, a shoe support, and means for moving the shoe toward operative position, said means including a continuously reciprocating drag link with means on one end for 15 engaging the support and being normally held out of operative relation to the support by arms which cause the reciprocating drag link to be held out of engagement with the support until after the initial manual movement of the support toward operating position. 20

ALFRED R. MORRILL.
